PORTABLE CASHIER TABLE

Delmar D. Rhoads, 3230 S. Calhoun St.,
Fort Wayne, Ind.

Filed June 9, 1958, Ser. No. 51,249

Term of patent 14 years

(Cl. D14—3)

I claim:

The ornamental design for a portable cashier table, substantially as shown and described.
